UNITED STATES PATENT OFFICE.

CHARLES MOSER, OF CINCINNATI, OHIO.

IMPROVEMENT IN CANS FOR PAINT, &c.

Specification forming part of Letters Patent No. 150,347, dated April 28, 1874; application filed April 16, 1874.

To all whom it may concern:

Be it known that I, CHARLES MOSER, of Cincinnati, Hamilton county, Ohio, have invented an Improved Can or Receptacle for Paint and other articles, of which the following is a specification:

My invention relates to a cylindrical can or box which is hermetically closed by simultaneously swaging the rim of the said can or box and the upturned lip of the cover, so as to impart to the same the form of a screw, and to at the same time enclose two gaskets, of which one is of tin or other soft metal, and the other of paper.

By this means the contents of the can are hermetically sealed, so as to be capable of being kept for any length of time, or transported from place to place, without injury to the contents, to which, however, access can be had at any moment by simply unscrewing the cover, an action which is rendered easy by the provision of an eye or socket on the top of the cover which is adapted to receive a nail or other like instrument for that purpose.

If only a portion of the contents is required, the can may be closed up again as completely as before.

In the accompanying drawings, Figure 1 is a perspective view, representing the members of my improved can detached. Fig. 2 is a vertical section through the upper part of the can, showing the cover in position, and before the swaging of the groove. Fig. 3 is a similar section after the groove has been turned. Fig. 4 is an enlarged view of the same.

A represents a cylindrical vessel whose mouth or opening is equal, or nearly so, to the

diameter of the cylinder. The sides of this vessel a little below the open margin are spun inward and again outward and upward, so as to present a shoulder, B, and an upturned rim, C. The lid or cover D is upturned exteriorly, so as to present a flange, E, which is of such dimensions, relatively, to the vessel as to permit the insertion of a paper gasket, F, below, and of a tin or other soft-metal gasket, G, above, which, having been inserted, the rim C and flange E, together with the soft-metal gasket G, are tightly and hermetically pressed or swaged together, so as to present the helical-threaded appearance shown at e e, Figs. 3 and 4. The central portion of the cover is formed crowning, and has (soldered or otherwise) firmly attached to it an eye or socket, H, for the insertion of any suitable wrench or lever when it is desired to open the can, or to subsequently close the same.

The paper, before use, may be saturated with stearine, paraffine, or other suitable substance; or, instead of paper, felt or cloth similarly saturated, caoutchouc, wash-leather, or other pliable substance, may be used.

I claim as new, and of my invention—

A paint-can composed of the open-mouthed cylindrical vessel A B C e, flanged cover D E e H, and gaskets F G, substantially as and for the purpose set forth.

In testimony of which invention I hereunto set my hand.

CHARLES MOSER.
